(57) **CLAIM**

The ornamental design for a modular magnetic mount, as shown and described.

DESCRIPTION

FIG. 1 is a front perspective view of a modular magnetic mount, showing my new design in a flat configuration; FIG. 2 is a front perspective view thereof, illustrated in a folded configuration;

FIG. 3 is a rear perspective view of FIG. 2;

FIG. 4 is a front elevational view of FIG. 1;

FIG. 5 is a rear elevational view of FIG. 1;

FIG. 6 is a left-side elevational view of FIG. 1, the right-side elevational view being a mirror image thereof;

FIG. 7 is a top plan view of FIG. 1;

FIG. 8 is a bottom plan view of FIG. 1;

FIG. 9 is a front elevational view of FIG. 2;

FIG. 10 is a rear elevational view of FIG. 2; and,

FIG. 11 is a right-side elevational view of FIG. 2, the left-side elevational view being a mirror image thereof.
